US00D976646S

(12) **United States Design Patent** (10) **Patent No.:** **US D976,646 S**
(45) **Date of Patent:** **** Jan. 31, 2023**

(54) **SMOKER DEVICE**

(71) Applicant: **Soak Limited**, Sandbach (GB)

(72) Inventor: **Robert Sumner**, Sandbach (GB)

(73) Assignee: **Soak Limited**, Sanbach (GB)

(**) Term: **15 Years**

(21) Appl. No.: **29/822,394**

(22) Filed: **Jan. 7, 2022**

Related U.S. Application Data

(63) Continuation of application No. 29/759,311, filed on Nov. 20, 2020, now Pat. No. Des. 944,594.

(57) **CLAIM**

The ornamental design for a smoker device, as shown and described.

DESCRIPTION

FIG. 1 is a front perspective view of a smoker device according to the new design;

FIG. 2 is a top plan view of the smoker device of FIG. 1; FIG. 3 is a side view of the smoker device of FIG. 1, the opposite view being a mirror image;

FIG. 4 is bottom plan view of the smoker device of FIG. 1; and,

FIG. 5 is an exploded view of the smoker device of FIG. 1. The broken lines are included for the purpose of illustrating portions of the device that form no part of the claimed design.

1 Claim, 5 Drawing Sheets
